UNITED STATES PATENT OFFICE.

GRANVILLE A. HUMASON, OF SHREVEPORT, LOUISIANA.

DRILL-BIT.

1,191,310.

Specification of Letters Patent. Patented July 18, 1916.

Application filed September 8, 1915. Serial No. 49,566.

To all whom it may concern:

Be it known that I, GRANVILLE A. HUMASON, a citizen of the United States, residing at Shreveport, in the parish of Caddo and State of Louisiana, have invented a new and useful Drill-Bit, of which the following is a specification.

This invention relates to drill bits, one of its objects being to provide means whereby the cutters of the bits can be readily detached and others substituted.

The structure is more especially designed for use in connection with bits of that type utilizing inclined side cutters and horizontal end cutters for use in cutting rock or gumbo.

Heretofore where inclined side cutters have been used the inner edges of the cutters have tended to become worn after long continued use and considerable difficulty has been experienced in substituting new cutters.

As before stated, one of the objects of the present invention is to provide means whereby the cutters of the bits can be readily detached and replaced or others substituted, the parts provided for holding the cutters in place being simple and durable in construction and being so assembled as not to come apart while the bit is in use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is an elevation of the drill bit embodying the present improvements. Fig. 2 is another elevation of the said bit viewed at right angles to Fig. 1. Fig. 3 is an enlarged section on

line A—B Fig. 1. Fig. 4 is a central longitudinal section through one of the holding plates of the bit. Fig. 5 is a similar view of another one of the holding plates. Fig. 6 is an elevation of the bearing of the horizontal cutters. Fig. 7 is a side elevation of one of the bearings of the side cutters. Fig. 8 is an end view of the bearing shown in Fig. 7.

Referring to the figures by characters of reference 1 designates the head of the bit 60 having its upper end reduced and threaded, as shown at 2. Formed within the outer surface of the head are longitudinally extending dovetail grooves 3 preferably equidistant as shown in Fig. 3.

Inwardly converging recesses 4 are formed in opposed portions of the head at the lower end thereof and two of the grooves 3 lead to these recesses. These two grooves are adapted to receive tongues 5 which are 70 dovetail and the lower ends of which are beveled, as at 6, so as to be parallel with the opposed walls of the recesses 4, the lower end portions of the tongues 5 thus constituting the outer side portions of the recesses. 75 Each tongue 5 has an inwardly extending shoulder 7 adapted to extend under and to abut against an inwardly extending shoulder 8 at the lower end of the groove 3 in which the tongue is seated, so that upward 80 thrust against the tongue 5 is thus communicated to the head 1. Tongue 5 is held to the head by means of screws 9 fitted within counter bore openings 10. Formed in the lower end portion of each tongue 5 is an 85 opening 11 having a recess 12 in the outer portion of the wall thereof. This opening is designed to receive a bearing pin 13 provided with a lug 14 adapted to occupy the recess 12 and thus to hold the pin against 90 rotation. Said pin is extended at right angles to the beveled face 6 of the tongue and has a split recessed end 15 which extends into a tapered opening 16 in the inner wall of recess 4, this wall dividing the recess 4 from a central end recess 17 in the head of the bit. The pin 13 is held in position across the recess 4 by inserting an expanding screw

18 into the recess in the split end of pin 13 with the result that said end will be expanded in the tapered opening 6 and pin 13 held securely against withdrawal. Mounted 5 on each pin 13 is an inclined side cutter 19 which can be of any desired form. For example, in the drawings a toothed cutter has been shown but it is to be understood that concavo-convex disks for use in cutting 10 gumbo, or any other suitable forms of side cutters can be employed. Obviously by removing the screws 18 the split ends of the pins 13 are free to contract and said pins can thus be withdrawn outwardly from the 15 openings 16 and 11, thus releasing the side cutters 19.

The ends of the recess 17 are open and the remaining dovetail grooves 3 in the head lead to these open ends of the recess. These 20 last mentioned grooves 3 are adapted to receive dovetail tongues 20 having counter bored openings 21 for the reception of holding screws 22 whereby the tongues are fastened to the head. Formed within the lower 25 end portions of the tongues are angular openings 23 and extending inwardly from each tongue 20 is a transverse stop rib 24 adapted to bear upwardly against the top wall of recess 17 thus to relieve the 30 screws 22 of strain due to upward thrusting against the tongue 20. Openings 23 receive the squared ends 25 of a bearing pin 26 and this pin is designed to support the horizontal cutters 27 which can be in 35 the form of toothed disks as shown or of any other shape desired. These cutters project upwardly into the recess 17 and are held against displacement along the bearing pin 26 by the tongues 20.

40 It will be obvious that whenever it is desired to remove the horizontal cutters 27, it is merely necessary to detach one or both of the tongues 20 from the head 1, whereupon the pin 26 will be released and the cutters can be removed from the pin and replaced or new cutters can be placed in position.

Importance is attached to the fact that all 50 of the tongues have means for transmitting end thrusts against the head 1, thus relieving the fastening screws of all strains during the operation of the bit. Furthermore, the ease with which the various cutters can be removed from and placed in position is important as is also the fact that cutters of different types can be assembled 55 with the bit herein described.

What is claimed is:

1. A drill bit including a head having a 60 groove, a tongue detachably mounted within the groove and retained by the walls thereof, means upon the tongue and coöperating with the head for transmitting longitudinal thrust from the tongue to the head, a bear-

ing pin detachably engaging the tongue, 65 and a cutter carried by the pin.

2. A drill bit including a head having a dovetail groove, a dovetail tongue seated in the groove, means for securing the tongue to the groove, coöperating means upon the 70 tongue and head for transmitting longitudinal thrust from the tongue to the head, a bearing pin detachably engaging the tongue, and a cutter carried by the pin.

3. A drill bit including a head having 75 spaced longitudinal grooves in the outer face thereof, tongues detachably mounted within the grooves and retained by the walls thereof, means upon the tongues coöperating with the head for transmitting longitudinal 80 thrusts from the tongues to the head, bearing pins having their outer ends detachably engaging the respective tongues and their inner ends engaging the head, and cutters mounted on the bearing pins. 85

4. In a drill bit the combination with a head having inwardly converging side recesses, there being longitudinal grooves in the outer face of the head and communicating with the recesses, of tongues detachably secured in and lapped and retained by the walls of the grooves and constituting the outer side walls of the side recesses, means upon each tongue and coöperating with the head for transmitting longitudinal thrust 95 from the tongue to the head, bearing pins detachably engaged by the tongues, and cutters mounted on the pins.

5. In a drill bit the combination with a head having inwardly converging side recesses, there being longitudinal grooves in the outer face of the head and communicating with the recesses, of tongues detachably secured in the grooves and constituting the outer side walls of the side recesses, means 100 upon each tongue and coöperating with the head for transmitting longitudinal thrust from the tongue to the head, bearing pins detachably engaged at their ends by the tongues, each of said pins having expandible 105 inner ends, means engaging said inner ends to expand them within the walls of the end recess, and cutters mounted on said pins and within the respective side recesses.

6. In a drill bit the combination with a 115 head having inwardly converging side recesses and longitudinal grooves opening into the recesses, of tongues detachably secured within the grooves and having their lower end portions constituting the outer side 120 walls of the converging recesses, each tongue having an opening therein provided with a recess in the wall thereof, there being a tapered opening within the inner wall of each of said inwardly converging recesses, 125 bearing pins extending transversely of the inwardly converging recesses and within the openings in the tongues, projections upon

said pins and seated in the recesses in the tongues, each pin having an expansible end seated within the adjacent tapered opening, means for expanding said end within said opening, and a cutting element mounted on each pin.

In testimony that I claim the foregoing

as my own, I have hereto affixed my signature in the presence of two witnesses.

GRANVILLE A. HUMASON.
